United States Patent Office

Des. 196,318
Patented Sept. 17, 1963

196,318

KEY CHARM OR SIMILAR ARTICLE

Harry C. Stalley, Jr., St. Clair Shores, Mich., assignor to
Wyandotte Chemicals Corporation, Wyandotte, Mich.,
a corporation of Michigan

Filed Aug. 17, 1961, Ser. No. 66,385

Term of patent 14 years

(Cl. D45—19)

Fig. 1.

Fig. 3.

Fig. 2.

FIG. 1 is a front elevational view of a key charm or similar article, showing my new design;

FIG. 2 is a rear elevational view thereof; and

FIG. 3 is a side elevational view thereof.

The essential features of my design reside in the portions shown in full lines in the drawings.

I claim:

The ornamental design for a key charm or similar article, as shown and described.
